(57) **CLAIM**

The ornamental design for a toothpick, as shown and described.

DESCRIPTION

FIG. 1 is a front perspective view of a toothpick in a first embodiment, showing the new design;

FIG. 2 is a rear perspective view thereof;

FIG. 3 is a left side elevation view thereof;

FIG. 4 is a front elevation view thereof;

FIG. 5 is a right side elevation view thereof;

FIG. 6 is a rear elevation view thereof;

FIG. 7 is a top view thereof;

FIG. 8 is a bottom view thereof;

FIG. 9 is a front perspective view of a toothpick in a second embodiment;

FIG. 10 is a rear perspective view thereof;

FIG. 11 is a left side elevation view thereof;

FIG. 12 is a front elevation view thereof;

FIG. 13 is a right side elevation view thereof;

FIG. 14 is a rear elevation view thereof;

FIG. 15 is a top view thereof; and,

FIG. 16 is a bottom view thereof.

The broken lines in the drawings depict portions of the toothpick that form no part of the claimed design.

1 Claim, 6 Drawing Sheets
